UNITED STATES PATENT OFFICE

2,609,684

CIRCUIT CONTROLLING ALTIMETER

Oscar S. Field and Sedgwick N. Wight, Rochester, N. Y., assignors to General Railway Signal Company, Rochester, N. Y.

Original application July 29, 1944, Serial No. 547,175. Divided and this application November 12, 1947, Serial No. 785,398

6 Claims. (Cl. 73—178)

1

This invention relates to airway traffic signalling systems, and more particularly pertains to a contact mechanism controlled in accordance with the altitude of an airplane for use in such systems.

The contact mechanism of the present invention is more particularly useful in an airway traffic signalling system in which airway traffic conditions in advance are indicated in the cab of an airplane automatically irrespective of weather and fog conditions such as shown in the parent application Ser. No. 547,175, filed July 29, 1944, now Patent No. 2,458,361, issued January 4, 1949. In other words, this application is a division as to the structural features of a contact mechanism for use in a complete signalling system such as shown in the parent application, which parent application is to be considered as an improvement over the prior applications of Wight et al., Ser. No. 517,814, filed January 11, 1944, now Patent No. 2,463,094, issued March 1, 1949, and Dicke Ser. No. 532,181, filed April 21, 1944, now Patent No. 2,439,846, issued April 20, 1948.

One of the objects of the present invention resides in the provision of means for operating a contact mechanism for manifesting an altitude at which an airplane is flying. This contact mechanism is to manifest such altitude in conformity with the indication given by a rather delicately designed altimeter. In accordance with this object of the present invention, it is proposed to employ a light beam which swings through an arc in accordance with the swing of an indicating point in an altimeter and in the provision of means for operating contacts to a position corresponding to the position assumed by such light beam through the medium of a selenium cell, photoelectric cell, or other suitable light responsive apparatus.

Other objects, purposes and characteristic features of the present invention will in part be described hereinafter and will in part be obvious from the accompanying drawings in which:

Fig. 1 illustrates conventionally an airplane equipped with airplane carried apparatus embodying the present invention; and

Figs. 2A, 2B, and 2C illustrate an altimeter controlled contact mechanism constituting part of the airplane carried mechanism illustrated in Fig. 1.

Since the subject matter of this divisional application relates to the structure and interrelation of parts of an altitude controlled contact mechanism for use in an air traffic signalling sys-

2

tem, it is believed expedient to briefly consider the other apparatus with which this mechanism is associated in an airplane. For this purpose, reference may be made to Fig. 1 of the drawings which shows the structure of the airplane carried apparatus.

STRUCTURE

Airplane carried structure.—Referring to Fig. 1 of the drawings, it will be observed that an airplane 1P2 has been illustrated equipped with suitable airplane carried radio communicating apparatus. Near the front of the airplane and constituting part of this apparatus is a scanning antenna SA which may be of any suitable construction but is preferably of a construction such as illustrated in the prior applications of Wight, Field and Saint, or Dicke, above referred to. This scanning antenna SA, illustrated conventionally as a directional antenna supported at right angles on a scanning shaft, is connected through the medium of a scanning receiver SAR, to suitable filtering apparatus FSI, and altimeter controlled contacts and a push button PB, to a kinescope including a screen S. By reference to the copending applications of Wight, Field and Saint, or Dicke, just referred to, it will be readily understood that this screen S will have displayed thereon pictorially each of the active ground radio transmitting stations in advance of the airplane within radio communicating distance, and juxtaposed thereon in substantially the same relation to each other as they are located in the field. It should be understood that the filter portions F2 and F3 of the filter FSI are constructed to admit only received radio energy characteristic of the altitudes 2 and 3, respectively. The particular characteristic frequency is then selected by the contact 20 of the altitude contact mechanism AC, as more specifically shown in Figs. 2A, 2B and 2C of the drawings.

This receiving apparatus also includes a hand knob HK which may be manually operated by the pilot, and by the use of which, the pilot may observe traffic conditions in advance in other altitudes than the particular altitude at which he is flying. It will be observed that the contact 20 controlled by the altimeter contactor AC is shown in the position 2 where it selects the filter portion F2 of the filter FSI which signifies that the airplane 1P2 is flying at altitude 2000 as a result of which there is indicated on the screen S traffic conditions in advance of this airplane 1P2 for altitude 2000. If now the pilot operates his hand knob HK to the 3 position, signifying an altitude of 3000 feet,

and if he then depresses the push button PB the screen S will be changed to indicate the same ground radio transmitting stations but with the spots identifying such stations flashing codes characteristic of those stations and also of traffic conditions in advance for altitude 3000. Similarly the contact 24 of the altimeter contactor selects the filter portion 12 of the filter FPI so that the airplane identifying code picked up by antenna PA is one which was radiated from the same altitude 2000 which was presumably coded by the coder 25 on the same airplane and radiated from the tail antenna TA of the same airplane but at a different carrier frequency, and received by the same or a different carrier frequency as passed by receiver SAR, it being received by receiver PR, and modulated to frequency 12.

As pointed out in the parent application, it is proposed to emit continuous energy producing a non-flashing spot on the screen under danger, that is, hold traffic conditions R, to code the radio energy by coding apparatus located at the ground station under consideration to flash the radio beam at a high rate for proceed traffic conditions G and at a low rate for normal traffic conditions N. By normal traffic conditions is meant the traffic conditions that normally exist, namely, that there is no airplane approaching such fix within two blocks or sections in the rear for the altitude in question (3000 foot altitude in the present case). It should be understood that even though a so-called normal radio beam may be emitted by a ground station this ground station may be potentially clear (N followed by dotted G), or may be potentially hold (N followed by dotted R). The filter FPI is, as above mentioned, provided with filter elements F12 and F13. The portions of the filter FSI identified by reference characters F2 and F3 signify altitudes 2000 and 3000 feet respectively, whereas the tens numeral 1 of the characters F12, F13, and so forth signifies that only radio energy shall pass therethrough which is characteristic of airplane identity for these altitudes but coded to identify the airplane on which it originated and not coded to signify traffic conditions in advance in this same altitude. This radio energy is received through the medium of receiver PR and filter FPI. In this connection, it should be understood that each airplane is provided with a tail transmitter TT which emits radio energy of carrier frequency F modulated to an altitude frequency selected by the contact 21 and emitted through the medium of a rearwardly directed tail antenna TA.

It will be observed that this tail transmitter TT transmits energy of carrier frequency F and of an altitude character 2, 3 or 4 depending upon the position assumed by the contact 21 of the altitude contact mechanism AC. In other words, when the airplane 1P2 is flying at the 2000 foot altitude, the contact 21 assumes the position 2; and if the airplane then advances to the 3000 foot altitude, the contact 21 will be automatically moved to select the modulating generator portion F3 of the modulating frequency generator FG. The airplane carried apparatus is also provided with a coder including a coding wheel 25 which codes the radio energy emitted by the tail antenna TA so as to characterize that particular plane.

In order for the pilot to conveniently make a continuous check as to the operativeness of his apparatus, a checking radio receiver CR has been

provided. This receiver has an antenna element located in the field of the tail antenna TA. This check receiver CR is provided with a filter FCI having associated filter elements F2, F3, etc. which are selected by the contact 22 of the altimeter contact mechanism AC. The energy picked up and selected by the particular filter element selected by the altimeter contact 22 may then flow through the relay W so as to cause this relay to follow the code of the radio beam emitted rearwardly by the airplane 1P2. It will be observed that the filter elements F12 and F13 of the filter FPI constitute a second checking instrumentation and are connected one at a time to the relay Y in accordance with the position then assumed by the contact 24 of the altimeter contactor AC.

From this consideration, it is readily understood that the relay W will pick up and drop in accordance with the code transmitted locally by the rearwardly directed tail antenna TA, whereas the relay Y will bob up and down in accordance with the radio energy generated at a ground radio transmitter, coded in accordance with the coded tail transmitted energy received at the next ground station in the rear. These relays W and Y are provided with contacts 27 and 28 which are included in correspondence circuits for the relay Z. This relay Z is rather quick acting and by reason of the fact that the two energizing circuits for this relay Z pass through back contacts and front contacts respectively associated with the movable contacts 27 and 28 of these relays, it is readily seen that the relay Z will only assume its picked up condition if the contacts 27 and 28 operate in perfect synchronism. In this connection, it should be understood that the contacts 27 and 28 are preferably make-before-break so that if these contacts 27 and 28 operate in synchronism, the energization of the relay Z is continuous in spite of code following operation of these contacts 27 and 28. These contacts 27 and 28 will of course operate in perfect synchronism if there are no other airplanes around, and if the airplane carried apparatus and the apparatus at both the first ground station ahead and the first ground station in the rear are in proper working condition.

The relay Z has associated therewith an indicating lamp ZL which will be lighted only when this relay Z assumes its energized condition. Similarly, the relays W and Y have associated therewith lamps WL and YL, respectively, which for obvious reasons are lighted only when the corresponding relay assumes its energized position. It should also be observed that the relay W has connected in multiple therewith a lamp 31, whereas the relay Y has connected in multiple therewith a lamp 32. These lamps 31 and 32 will of course follow the code characters impressed on these relays W and Y respectively. In this connection it should be understood that the lamps 31 and 32 may only be used in the event the lamps WL and YL, respectively, are omitted and that in practice the relay Z and its associated lamp ZL may be omitted if desired, it being understood that the correspondence between the transmitted code and the received code may be observed from the lamps 31 and 32 flashing in synchronism. If the relay Z is omitted for this reason, the relays W and Y may also be omitted in which event the lamps 31 and 32 alone will be relied upon for the desired check information.

Although many of the devices illustrated in

Fig. 1 have been shown rather conventionally, it is believed that this conventional showing is sufficient in view of the advanced status of the art in radio communication. It may, however, be pointed out that suitable generators are associated with the scanning antenna SA for the purpose of generating voltages for application to the sweep plates of the kinescope including the screen S, and these generators have been specifically disclosed in the applications of Wight et al. and Dicke, above referred to. The letter F assigned to the filters FPI and FSI signify that the carrier frequency received by the scanning antenna receiver SAR is of carrier frequency f , whereas the characters F2, F3, F12 and F13 signify four different kinds of modulating frequency superimposed on this carrier frequency f . As above pointed out two distinct carrier frequencies may be used. It may be pointed out that of these modulating frequencies the frequencies F2 and F12 have been assigned to altitude 2000, the frequencies F3 and F13 have been assigned to altitude 3000, and the frequencies F4 and F14 would have been assigned to altitude 4000 if it had been illustrated. The modulating frequency generator FG associated with the tail transmitter TT is capable of generating current of carrier frequency F which is modulated at frequencies F2 or F3 depending upon the particular altitude 2000 or 3000 at which the airplane is flying as determined by altimeter contact 21 (Figs. 1, 2A and 2C). The filter FCI associated with the check receiver CR is of course constructed to receive carrier frequency F modulated at modulating frequencies F2 or F3 depending upon the position then assumed by the contact 22 of the altimeter contact mechanism AC. Both of the carrier frequencies F and f proposed to be employed in the present system are ultra-ultra-short-wave length frequencies in order that the antenna SA may be highly directional. The tail antenna TA preferably emits radio energy spread in a conical direction throughout an angle of substantially 90° whereas the individually focused radio antennae, four of which have been illustrated, of the scanning antenna SA will only receive radio energy within very small spread of the focal axis of the particular receiving antenna focusing cup then effective. This angle of spread is preferably about two to five degrees.

Let us now refer to Figs. 2A and 2B of the drawings and observe the construction of the altimeter contact mechanism AC shown conventionally in Fig. 1 of the drawings and illustrated more specifically in Figs. 2A, 2B and 2C.

Referring to Fig. 2A, the altimeter contact mechanism includes a bellows or Sylphon SY which is evacuated and which has a collapsing tendency against the force of the spring 35 depending on the atmospheric pressure and therefore depending on the altitude at which the airplane is flying. This "sylphon" SY is held in a predetermined expanded condition depending upon the atmospheric pressure by a U-shaped spring 35 and is provided with an arm 36 which will sweep about the U-shaped part of the spring 35 as a pivot through an arc dependent upon the change in atmospheric pressure and will thereby, through the medium of the arm 36 and the link 37, rock the angle lever 38 supported for movement about a pin 39 so as to cause the arm 38 to pull or release the chain 41 against the tension of the hair spring 30, depending upon whether the atmospheric pressure is rising or falling respectively. As a result of this action, the pointer 45 is operated through the medium of the drum 44 in a clockwise direction if the atmospheric

pressure is falling (altitude increasing) and in a counter-clockwise direction when the atmospheric pressure is increasing (altitude decreasing). In other words, the altitude indicating pointer 45 is moved in a clockwise direction as the altitude of the airplane is increased.

In order to have the pointer 45 indicate the altitude accurately in spite of variations of the atmospheric pressure at sea level, the manually operable adjusting knob AK is provided to adjust the position of the dial plate 47. This dial plate 47 may be adjusted by the pilot in accordance with information received by him through the medium of radio communication, and may be adjusted to a position to indicate with respect to a stationary pointer 34 the atmospheric pressure at sea level for that particular locality. This turning of the manually operable knob AK, through the medium of the pinion 46, will rotate the toothed scale plate 47 with respect to which plate, the pointer 45 is read. In other words, if the knob AK is adjusted to indicate atmospheric pressure at sea level by pointer 34, the pointer 45 will indicate the altitude at which the airplane is flying under this atmospheric pressure condition. It is this latter construction that distinguishes the altimeter from a barometer. At the end of the shaft 43, on which the chain drum 44 and pointer 45 are supported, is provided a mirror MI for purposes presently to be described.

A suitable light source such as a lamp L is provided on the axis of the shaft 43 beyond the mirror MI. Between this lamp L and the mirror MI is provided a condensing lens CL which concentrates the light emitted by the lamp L into a narrow beam striking the mirror MI at the point substantially on the axis of the shaft 43. It is readily seen that by this construction the light beam reflected by the mirror MI will rotate in a plane at right angles to the axis of this shaft 43 and that this light beam will rotate in exact synchronism with rotation of the shaft 43. Adjacent this rotating light beam is provided a wheel rim 48 which supports two light responsive cells LC1 and LC2. These light responsive cells are included in the circuits of relay DR and UR respectively. These cells may be of selenium construction but are preferably light responsive cells of the photo-electric type. The cell LC1 is shown included in a circuit which may be traced from the terminal (+) of a suitable source of current, slip ring 40, through cell LC1, winding of the down relay DR, and back contact 49 of the up relay UR, to the terminal (-). It is of course understood that in practice suitable amplifying means, not shown, may be employed to amplify the current produced by the photo-electric cell. A similar circuit for the relay UR may be traced from the terminal (+), slip ring 40, through the light responsive cell LC2, winding of the relay UR, and back contact 50 of the relay DR to the terminal (-). These relays DR and UR are provided with contacts 51, 52, 53 and 54 which for obvious reasons will cause current of one polarity or the other to be applied to the motor M of the permanent magnet field type or induction type, the polarity depending upon which of the two relays DR or UR assumes its energized condition.

It will be observed that the relay DR may be picked up by depression of the push button contact PD, whereas the relay UR may be picked up by depression of the push button contact PU. These push button contacts are provided for test purposes and should not be used during route flying. It will be observed (see Fig. 2A) that the motor M (also shown in Fig. 2C) is operatively

connected to the gear 42 rigid with rim 48 through the medium of the gear 55. It is thus readily seen that if the pointer 45 and the light beam are moved clockwise by the altimeter from its normal position in which the light beam strikes between the two light responsive cells, this light beam will impinge on the light responsive cell LC2 thereby causing the flow of current through the relay UR which results in the operation of the motor M in a direction to cause clockwise rotation of the rim 48 (as viewed from the right in Fig. 2A) to cause the two light responsive cells LC1 and LC2 to again assume positions on opposite sides of the light beam in its new location. In other words, the light responsive cells LC1 and LC2 are caused to assume positions corresponding to the position assumed by the altitude pointer 45.

In practice, the dial 47 back of pointer 45 is provided with indications indicating only altitudes up to an altitude of 10,000 feet whereas in practice airplanes will fly in altitudes up to 20,000 feet. In other words, the pilot must be relied upon to properly read and interpret the altimeter including the pointer 45. In order to provide contacts which complete a different circuit for each altitude between 1000 feet and 20,000 feet, contact arms 20, 21, 22 and 24, of which the contact arm 21 only has been shown, are provided (see Fig. 1). These contact mechanisms are driven through gear mechanism so as to rotate only one complete revolution for two complete revolutions of the pointer 45. This gear reduction is provided through the medium of the gears 42 and 57, the gear 57 having twice the diameter of gear 42. The contact arms, 20, 22 and 24 are also carried by the shaft 53 which carries the contact arm 21. Of these contact arms 20, 21, 22 and 24, the arm 21 is more specifically shown in Figs. 2A and 2C of the drawings. In order to provide an additional indicator which does not require interpretation by the pilot as to whether he is flying in the first 10,000 feet of altitudes or the second 10,000 feet of altitudes a second pointer 60 (see Figs. 2A and 2C), which rotates only half as fast as shaft 43, has been provided to visually indicate the actual altitude at which the airplane is flying.

With the structure above described, it will therefore be apparent that each airplane radiates rearwardly directed energy characteristic of the altitude at which the airplane is flying and coded at a rate to characterize the particular airplane.

Also, the system of the present invention has been designed so that the pilot of each airplane by looking upon the screen of his kinescope will see the way stations in advance of him on the screen and coded to manifest traffic conditions in advance for the particular altitude at which he is flying. This is true because the altimeter contact mechanism in Figs. 2A, 2B and 2C will tune his radio receiver for the modulated frequency assigned to the particular altitude at which the airplane is flying, as shown by contacts 20 of the altimeter contactor AC (Fig. 1). The pilot is, however, provided with a hand knob HK (Fig. 1) and a push button PB through the medium of which he may look into another altitude so to speak by adjusting this hand knob HK for such other altitude and by depressing the push button PB. By "look into" is meant—cause his kinescope to display traffic conditions in such other altitude.

Let us now assume that the pilot of airplane

IP2 (Fig. 1) desires to change altitude because of another airplane IP4 (not shown) in advance thereof. Let us first assume that he turns his hand-knob HK to the 3 position and depresses his push button PB (Fig. 1). This operation will enable the pilot of the airplane IP2 to observe an indication G-over-G as shown for altitude 3 at fixes B and A, as shown in said parent application. The pilot will of course know that it is unsafe for him to descend to altitude 3000 because he is informed by this indication G-and-G that there is an airplane in the 3000 foot altitude and in the same section or block in which he is flying.

Let us now assume that the pilot turns his hand-knob HK to the 5 position and then depresses the push button PB. He will then observe an indication of N-over-N signifying that he may ascend to the 5000 foot altitude with safety. This N-over-N indication signifies no airplane at altitude 5000 in the same section nor the section ahead or behind the section in which airplane IP2 is flying. Let us now assume that he starts to climb with his airplane IP2 and as he almost reaches altitude 5000 his altimeter contact mechanism AC will manifest the 5000 foot altitude and will not only through the medium of its contact 20 cause his screen S to display traffic conditions in altitude 5000 but will also cause the tail energy emitted by his airplane IP2 to be modulated to the 5000 foot altitude modulating frequency. While the pilot of airplane IP2 was making this ascent he would be expected to continue to keep his push button depressed with his hand-knob HK on the 5 position, this by reason of the fact that traffic conditions might change in the 5000 foot altitude while he is making the ascent. If we assume that a change of traffic condition did take place before his altimeter indicated the 5000 foot altitude, the pilot being informed as to the indication displayed by his contact making altimeter, he would of course know that this change in indication from N-over-N to some other indication was due to another airplane if his contact making altimeter has not yet manifested a 5000 foot altitude.

The applicants have thus disclosed a cab signalling system including airplane carried apparatus having a contact mechanism controlled in accordance with the altitude at which the airplane is flying, and this contact mechanism is effective to govern both the received signals and the transmitted signals so as to cooperate with suitable ground located apparatus to provide the desired indications both in the airplane and on the ground. Although one particular structure of contact mechanism has been shown herein, it should be understood that various changes, modifications, and additions may be made to adapt the invention to the particular problem encountered in practicing the invention without departing from the spirit or scope of the invention except as demanded by the scope of the following claims.

What we claim is:

1. An altimeter device for operating contacts in accordance with altitude comprising, an aneroid barometer including a fixed pointer cooperating with a movable dial having a barometric scale, manually operable means for moving said dial to a position where the pointer indicates a given barometric pressure, a shaft turned by said barometer to different positions in accordance with the atmospheric pressure

then acting on said barometer, a multiple position altitude contactor having two relatively movable contact elements, a follow-up system including light responsive devices and operatively connecting said shaft with one of said contact elements, and means directly connecting said dial and the other of said contact elements, whereby a manual setting of the dial in accordance with the existing barometric pressure in a given region with respect to sea level will cause said multiple position contactor to take a position corresponding with the altitude location of the altimeter device.

2. A contact making altimeter for airplanes comprising, an aneroid barometer including a movable pointer operated to different positions for varying atmospheric pressures, a fixed pointer, a movable dial adjacent said pointers, said dial having an altitude scale adjacent said movable pointer and a barometric scale adjacent said fixed pointer, a multiple position contactor having an adjustable contact carrying element with a plurality of fixed contacts mounted thereon for different preselected altitudes indicated on said altitude scale and also having a movable contact arm operative to co-act with said fixed contacts of said contact carrying element, a follow-up system including light sensitive devices governed by said barometer and a motor operatively connected to said movable contact arm to thereby effect operation of the contact arm to correspond with changes in air pressure, a manually operable means for adjusting said movable dial with respect to said fixed pointer, and a mechanical driving connection between said movable dial and said adjustable contact carrying element, whereby the operation of said manually operable adjusting means to set said dial with respect to said fixed pointer to correspond to the existing barometric pressure in a given region with respect to sea level causes said movable pointer and said contact arm to assume positions corresponding with the altitude at which the airplane is then travelling.

3. A contact making altimeter for airplanes comprising, an aneroid barometer, a rotary shaft operated by said barometer to different positions in accordance with the atmospheric pressure acting thereon as the altimeter is carried to different altitudes by the airplane, said shaft making more than one revolution for the range of altitudes the airplane may occupy in flight, a multiple position rotary circuit controller having two relatively movable contact elements with a number of contacting positions corresponding to selected altitudes of said range of altitudes, a motor driven element, a follow-up system including light responsive devices and operatively connecting said shaft and motor driven element to cause said motor driven element to assume rotated positions corresponding with those of said shaft, a mechanical connection including the required reduction gearing between said motor driven element and one of the movable contact elements of said circuit controller to cause said circuit controller to assume different contacting positions for the different altitudes of flight of the airplane for the same rotated positions of said shaft as it makes more than one revolution, and means for manually adjusting the position of the other of said movable contact elements in accordance with the existing barometric pressure in a given region with respect to sea level.

4. A contact making altimeter for airplanes comprising, an aneroid barometer, a rotary shaft

operated by said barometer to different positions in accordance with varying atmospheric pressure, said shaft making more than one revolution for the range of altitudes through which the airplane may travel, a movable dial having a barometric scale adjacent a fixed reference point and also having an altitude scale, a movable pointer mounted on said shaft and movable with respect to said altitude scale, a multiple position rotary circuit controller having a rotary contact element cooperating with an adjustable contact element, a motor driven element, a follow-up system including light responsive devices, said system operatively connecting said shaft and said motor driven element to cause said element to assume rotated positions corresponding with those of said shaft, a mechanical connection between said motor driven element and said rotary contact element including reduction gearing of a particular ratio, manually operable means for moving said dial to a position to conform with a given barometric pressure with respect to sea level, and a mechanical connection between said dial and said adjustable contact element having a reduction gear ratio corresponding to said particular ratio, whereby said movable dial and said adjustable contact element can be simultaneously set in accordance with changing atmospheric pressures with respect to sea level for a region although said shaft in making more than one revolution assumes the same rotated positions for different altitudes.

5. A contact making altimeter for airplanes comprising, an aneroid barometer, a shaft operated by said barometer to different positions in accordance with the atmospheric pressure acting thereon, a movable dial having a barometric scale and an altitude scale, a pointer on said shaft cooperating with said altitude scale, a multiple position circuit controller having a rotary contact element cooperating with an adjustable contact element carrying a contact for each of a plurality of different altitude positions of the rotary contact element, a follow-up system including light responsive devices and operatively connecting said shaft with said rotary contact element, manually operable means moving said dial and said adjustable contact element simultaneously to positions to conform with a given barometric pressure with respect to sea level, and an indicating means including another altitude scale and another pointer connected with the respective contact elements of said circuit controller, said pointers and altitude scales enabling a comparison to be made between the contacting position of said circuit controller and the position of said shaft, and thereby determine whether or not said follow-up system has been effective to operate said circuit controller in accordance with changes in altitude.

6. A contact making altimeter for airplanes comprising, an aneroid barometer, a rotary shaft operated by said barometer to different positions in accordance with the different atmospheric pressures as the altimeter is carried to different altitudes by the airplane, said shaft making more than one revolution for the range of altitudes through which the airplane may travel, a multiple position rotary circuit controller having two relatively movable contact members, a follow-up system including a motor operable in either direction, a driven element operated by said motor, two light responsive means mounted on said driven element, a mirror mounted on said rotary shaft and operated by said barometer to direct

11

a beam of light to one or the other of said light responsive means in accordance with the direction of pressure changes, two relays each respectively connected to one of said light responsive means, circuit means governed by said relays for operating said motor in one direction or the other depending upon which relay is then operated, a mechanical connection between said driven element and one element of said multiple position contact means, a manually operable contact connected to each relay for individually energizing that relay, whereby said circuit controller can be manually operated to cause said contact element to assume a position corresponding to the existing position of said shaft. 15
